UNITED STATES PATENT OFFICE

EDWIN R. SMITH AND RICHARD A. ASHTON, OF SENECA FALLS, NEW YORK, ASSIGNEES TO SENECA FALLS MACHINE CO., OF SENECA FALLS, NEW YORK, A CORPORATION OF MASSACHUSETTS

CAM-ACTUATED LATHE

Application filed March 3, 1926. Serial No. 92,030.

This invention relates to a lathe adapted for turning cylinders or other work and particularly designed for producing duplicate parts in large quantities.

5 It is the object of our invention to improve the construction of such lathes in many important respects, thereby producing increased speed and efficiency, and enabling the operator to turn out duplicate parts very rapidly.

With this general object in view, important features of our invention relate to the provision of direct-acting cam mechanism for moving the tool carriage axially of the 15 lathe; to the provision of additional direct-acting cam mechanism for moving the tool slides toward and from the work; to the provision of automatic devices for changing the speed of the work spindles at desired points 20 in the operation of the lathe and also for increasing the speed of the actuating cams during the idle or return movements of the tool carriage. We have also provided means for automatically stopping the machine at a 25 given point in the operation thereof and we have provided a safety release device to prevent injury to the driving mechanism of the machine in the event of accidental obstruction to the movement of the tool carriage.

Our invention also relates to certain arrangements and combinations of parts which will be hereinafter described and more particularly pointed out in the appended claims.

35 A preferred form of the invention is shown in the drawings in which

Fig. 1 is a front elevation of our improved machine;

40 Fig. 2 is an end view, looking in the direction of the arrow 2 in Fig. 1;

Fig. 3 is a partial plan view, looking in the direction of the arrow 3 in Fig. 1;

Fig. 16 is a sectional side elevation thereof, taken along the line 16-16 in Fig. 15, and

Fig. 17 is a development of the surface of one of the cams shown in Fig. 16.

General outline of the machine

Referring to the drawings, we have shown a lathe comprising a frame A having a work driving head B, a tail-stock C and a tool carriage D. The tail-stock C is mounted in guideways for axial movement on the frame A and is in general of the usual construction. The tool carriage D (Fig. 16) is mounted on a guide-way 20 and a steel gib 21 and is movable axially of the lathe by a mechanism to be described. A clamp 21a holds the carriage in position on its guideways. This construction leaves the rear upper part of the frame free for other attachments.

The work W (Fig. 3) may be supported upon centers 23 and 24 in the head stock B and the tailstock C respectively and is engaged by tools T secured in cross slides 25 mounted for transverse movement in the tool carriage D by special cross feeding mechanism to be described. The head center 23 is mounted in a work spindle 30 and the work may be provided with a dog 31 of any con-

venient form by which driving engagement with the spindle 30 may be effected.

Spindle driving mechanism

5 We will now describe the mechanism for driving the work spindle 30. A motor 32 (Fig. 2) is mounted on the frame A and is connected by a belt 33 to a pulley 34 which is loosely rotatable on a main drive shaft 35 (Fig. 4). A clutch operating ring 36 is 10 slideable on the shaft 35 to control the disc clutch assembled in the hub 34a of the pulley 34 for driving the shaft 35. The ring 36 is positioned by a yoke lever 37 on a cross shaft 38 having an arm 39 connected by an adjustable link 40 to an arm 41 on a starting shaft 42. A second arm 43 on the shaft 42 is engaged by a spring 44 attached to a fixed point 15 on the frame A. This shaft 42 is also provided with a handle 45 for actuating the clutch.

The handle 45 has a lateral projection 46 with a lock plate 47 fixed thereon in position for engagement by a lug 48 on an arm 49 which is mounted on a cross shaft 50. A 20 stopping handle 51 is also mounted on the shaft 50 and is provided with a compression spring 52 which normally moves the handle 51 upwardly, carrying the lug 48 to a position to engage the lock plate 47.

When the starting handle 45 is depressed to engage the clutch 36, the lock plate 47 will be caught by the lug 48 and the lathe will remain in operation until the stopping handle 35 51 is depressed to release the clutch. Provision is also made for automatic release of the clutch, which mechanism will be hereinafter described.

The main drive shaft 35 (Fig. 6) is provided with a pinion 55 engaging a gear 56 fast on an upper drive shaft 57 (Fig. 5). A pinion 58 is keyed to the shaft 57 and engages a gear 59 on an intermediate shaft 60. A gear 61 on the shaft 60 engages a large gear 62 on the work spindle 30. A continuous low-speed drive is thus provided between the main drive shaft 35 and the work spindle 30.

An additional gear 63 is loosely mounted on the upper drive shaft 57 and is provided 50 with a clutch member 64 positioned for engagement by a second clutch member 65 keyed to the shaft 57. A yoke lever 66 is mounted on a vertical shaft 67 and is provided with means by which the yoke may be 55 shifted automatically to cause the clutch members 64 and 65 to engage, thereby rotating the spindle 30 at a higher speed, as the ratio between the gears 63 and 61 is greater than the ratio between the pinion 58 and 60 the gear 59.

The gear 59 is secured to the intermediate shaft 60 by a ratchet clutch which permits the shaft 60 to over-run the gear 59, when the shaft is rotated at higher speed. We 65 have thus provided a second driving connec-

tion between the main shaft 35 and the spindle 30, by which the spindle may be rotated at a higher speed than would take place through the gear train first described.

Cam shaft drive

70

We will now describe the connections for driving the cams which actuate the tool carriage. For this purpose, we provide a worm 70 (Fig. 5) on the intermediate shaft 60 previously described. The worm 70 meshes with a worm gear 71 (Fig. 6) on a vertical shaft 72 connected by bevel gears 73 and 74 (Fig. 8) to a lower intermediate shaft 75. A pinion 76 on the shaft 75 engages a gear 77 on a second intermediate shaft 78, which latter shaft is provided with a gear 79 engaging a gear 80 loosely mounted on a worm shaft 81 and connected thereto by an over-running ratchet clutch mechanism to be described and shown in detail in Fig. 10.

80 A worm 82 on the shaft 81 engages a large worm wheel 83 (Fig. 11) on a short shaft or stud 84. A pinion 85 is fixed to the worm wheel 83 and engages gears 86 and 87 on a pair of cam shafts 88 and 89 to which are secured the carriage actuating cams 90 and 91 (Fig. 13). These cams oppositely engage a cam roll 92 mounted on a bracket 93 secured to a pull rod 94 which is slideable axially in the machine frame A and which is suitably connected to the tool carriage D for moving the carriage along the guide-ways 20 and 21 previously described. The pull rod 94 may conveniently be made in two parts threaded 85 together as indicated in Fig. 13.

Safety device

90

The worm shaft 81 (Fig. 9) is also preferably made in two parts connected by clutch members 96 and 97 having co-operating teeth on their engaging faces. The member 97 is slideable on the shaft 81 and is pressed yielding toward the member 96 by springs 98, one of which is shown in Fig. 9.

105 The position of the clutch member 97 is controlled by a yoke lever 99 connected by a link 100 to a release handle 101 (Figs. 1 and 2). By swinging the handle outward, the yoke lever 99 may be moved to the left in Fig. 9, thus separating the clutch members 96 and 97 and stopping the rotation of the carriage-actuating cams 90 and 91.

110 It is often convenient to thus disconnect the carriage drive, when it is desired to separately move the spindle without corresponding movement of the carriage. This yielding clutch connection between the two parts of the worm shaft 81 also permits the parts to slip, in case further movement of the carriage is obstructed and thus prevents breakage of the driving mechanism.

Clutch construction

115 The over-running clutch between the gear

120

80 and the shaft 81 is shown in detail in Figs. 9 and 10. A ratchet member 103 is keyed to the shaft 81 and is provided with ratchet teeth 104 positioned for engagement by a 5 pawl 105 pivotally mounted in a recess 106 in the continuously rotated gear 80.

Under normal conditions, the gear 80 drives the shaft 81 through engagement of the pawl 105 with the teeth 104 of the ratchet member 103. Provision is made, however, 10 for rotating the worm shaft 81 at a higher speed and when this occurs, the ratchet members 103 over-runs the pawl 105.

The ratchet member is provided with a 15 spring 107 frictionally embracing said ratchet member and having its ends slightly separated as indicated at 108 in Fig. 10. The pawl 105 has a pin 109 which is received in the notch 108 in the spring 107.

20 When the shaft 81 is rotated at a higher speed than the gear 80, the spring 107 is frictionally pushed ahead of the gear 80, swinging the pawl 105 by its pin 109 out of engagement with the ratchet teeth 104. This 25 reduces the wear of the ratchet teeth and pawl and also eliminates the noise which would otherwise be made by the over-running clutch.

High speed drive and control

30 The high speed drive of the worm shaft 81 is obtained direct from the main drive shaft 35 (Fig. 2) through a pulley 110, a belt 111 and a pulley 112. The pulley 112 is loose on the worm shaft 81 but may be secured thereto by a friction clutch 113 controlled by a yoke arm 114 on a cross rod 115.

The rod 115 extends rearward in the frame A, as indicated in Fig. 11, and at its rear 40 end is provided with an upwardly extending arm 116 (Fig. 12), the forked end of which is positioned between lock nuts 117 on a control rod 118. The rod 118 extends axially in the frame A and the right hand end of 45 the rod, as viewed in Fig. 11, engages a drum 120 on the carriage-actuating cam shaft 88 previously described.

Whenever a cam lug or projection 121 on the drum 120 engages the rod 118, the rod is 50 forced to the left against the pressure of a spring 119, rocking the cross rod 115 in an anti-clockwise direction, as viewed in Fig. 9, and thus disconnecting the high speed drive.

55 Similar cam lugs or projections 122 (Fig. 6) mounted on a rear portion of the drum 120 engage an arm 123 on the shaft 67 previously described and a spring 124 (Fig. 7) holds the arm 123 in engagement with the 60 drum 120. When the arm 123 is moved by the lug 122, the arm 66 (Fig. 5) is correspondingly moved to withdraw the clutch member 65 from the clutch member 64, thus causing the spindle 30 to rotate at relatively slow 65 speed.

Stopping mechanism

The mechanism for automatically stopping the operation of the machine comprises a trip 130 (Fig. 4) mounted on the cam 90 and positioned to engage and raise a plunger 131 mounted in the casing or frame A and engaging an arm 132 on the cross shaft 50 to which the stopping handle 51 is secured. When the plunger is raised by the trip 130, 70 the stopping handle is depressed and the lock plate 47 is released as previously described, causing the machine to come to rest. A spring 133 on the plunger 131 seats the plunger in its bearing and quickly returns it to normal position, after being raised by the strip 130. 75

Tool carriage drive

The tool carriage D is moved axially by the pull rod 94 having the cam roll bracket 93 clamped thereon, as previously described. 80 The longitudinal position of the carriage may be adjusted by loosening the clamps of the bracket 93 and moving the carriage or rotating the cams to bring the pull rod and clamps to a desired relation. Further axial adjustment of the tool carriage D may be accomplished by adjusting the clamps 140 and 141 (Fig. 1) on the pull rod 94 which engage the carriage D at both sides thereof. 85

By spacing the clamps or collars 140 and 141 further apart than the width of the carriage D, lost motion may be introduced and the carriage D may be given a sliding motion of less extent than the actual movement of the rod 94. In this manner, various reduced 90 motions of the carriage D may be obtained from a single set of cams 90 and 91.

The two portions of the shaft 94 may also be relatively adjusted axially by loosening the lock nut or collar 142 (Fig. 13) and rotating one part of the shaft relatively to the other on its screw-threaded connection. 100

Angular movement of the left hand or head end portion of the shaft 94 is prevented by 105 extending the bracket 93 downward, as indicated in Figs. 13 and 14, and by providing a guide block 143 at the lower end of the bracket which guide block travels in a guide-way on a recessed guide bar 144. The bracket 110 93 and pull rod 94 are thus securely held from angular movement. 115

Cross feeding mechanism

We will now describe the mechanism for 120 moving the tool slides toward and from the work. The worm shaft 81 (Fig. 9) is connected by a swivel shaft 150 (Fig. 1) to a cross feed shaft 151 (Figs. 15 and 16). One or more worms 152 are mounted on the cross 125 feed shaft 151, each worm engaging a worm wheel 153 (Fig. 16) on a short shaft 154 rotatable in bearings in the tool carriage D and having a pinion 155 fixed thereto.

The pinion 155 engages a gear 156 rotat- 130

able on a shaft 157 and having a drum 158 secured thereto. Cam plates 159 (Fig. 17) are secured to the drum 158 to give the tool slide 160 any desired movements toward and from the work, the tool slide being provided with a cam roll 161 engaging the cam plates 159. A spring plunger 162 is provided for pressing the tool slide away from the work, and thus taking up any back-lash between the cam plate 159 and the cam roll 161.

The drum shaft 157 is rotatable at its rear end in a bearing 163 in the tool carriage D and at the opposite end is supported in a sleeve 164 threaded into the casing of the carriage D. The shaft 157 is keyed to the sleeve 164 and the rear portion of the shaft is enlarged to provide a head for retaining the drum 158 on the shaft. A thrust bearing 158a may be provided between the drum 158 and the sleeve 164. End play of the shaft and drum may be taken up by check nuts 165 on the shaft 157. The front outer end of the shaft is flattened as indicated in Fig. 15 to receive a wrench or spanner.

By turning the shaft 157, the sleeve 164 is also turned in its threaded bearing and the shaft 157 and drum 158 may thus be moved axially for slight adjustment of the tool T toward or from the work. The outer end of the sleeve 164 may be graduated at 166 to co-operate with an index line 167 on the casing D, thus indicating the amount of radial adjustment of the tool T.

It will be understood that as many tool slides 160 may be provided upon the tool carriage as are found necessary for the particular type of work which the machine is designed to handle and a corresponding number of worms 152, drums 158 and gear connections will be provided to actuate the different tool slides. The cam plates 159 may be varied for the different drums so that the tools may be advanced or withdrawn, either separately or simultaneously, as may be desired.

General operation

Having thus described the details of construction of our improved lathe, it is believed that the general operation thereof will be readily apparent. The lathe is designed particularly for producing large number of duplicate parts and for such purposes the cams 90 and 91 and the cam plates 159 on the drums 158 may be specially designed for the work to be handled.

Assuming that the machine has been provided with suitable cams and cam plates for a particular piece of work, such for instance as is indicated at W in Fig. 3, the machine may then be started in operation by depressing the starting handle 45 to cause the clutch 36 on the main drive shaft to engage the driving pulley 34.

At the time of starting, the cam lugs 121

and 122 (Figs. 6 and 11) will commonly be out of engagement with the rod 118 (Fig. 11) and the arm 123 (Fig. 6). The clutch 113 (Fig. 9) will thus be engaged so that the worm shaft 81 will be rotated at high speed and will act through the cams 90 and 91 to move the tool carriage D rapidly to operative position. The cams 90 and 91 may also be designed as to increase the relative speed at this point in the operation of the machine.

The clutch members 64 and 65 (Fig. 5) may at this time be set to rotate the spindle 30 at either high or low speed. If it is then desired to reduce the speed of the worm shaft 81 to a lower cutting feed, the cam lug 121 (Fig. 11) may be set to engage the rod 118, disconnecting the clutch 113 (Fig. 9) and permitting the worm shaft 81 to be rotated in geared relation with the spindle 30.

If the clutch members 64 and 65 are engaged for high spindle speed and the heavy portion of the cut is reached or if for any other reason a slower speed is desired, the cam lug 122 (Fig. 6) may be positioned to engage the arm 123, disconnecting the clutch members 64 and 65 causing the spindle 30 and worm shaft 81 to be driven through the low speed gears 58 and 59 (Fig. 5).

At the end of the cut, the cam lug 121 will pass out from under the rod 118, permitting the tool carriage D to be returned to its inoperative position at high speed. The trip 130 (Fig. 4) then engages the plunger 131 and stops the machine.

If it is desired to stop the machine at any intermediate point, this may be easily done by using the stopping lever 51. Furthermore, if it is desired to stop both the longitudinal and cross feed of the tool carriage, while continuing the rotation of the spindle, this may be done by movement of the handle 101 (Fig. 2) to cause separation of the clutch members 96 and 97 (Fig. 9).

It will thus be seen that we have provided mechanism for advancing and returning the tool carriage D at various speeds, as well as for advancing and retracting the tool slides 160, all during the continued rotation of the work spindle 30 and work W in a single direction.

Obviously the cams 90 and 91 and the cam plates 159 may be designed to produce any desired operations on the work. By suitably designing the cams 90 and 91, the tool carriage may, if desired, be given a double transverse for a single rotation of the cams and the cam plates 159 may be designed to advance the tool first for a roughing cut during the first transverse and then for a finishing cut during the second traverse, all without stopping the machine and without reversing the rotation of the work spindle.

Many other useful combinations may be worked out by suitably designing the cams

and cam plates. These may also be designed to cooperate to advance the tool toward working position along the path of the dotted line *a* in Fig. 3, thus substantially reducing the time of operation and bringing the tool into engagement with the work with the least possible delay. While we have shown the lathe as of the horizontal type, the utility of our invention is not limited thereto, as many of the features thereof are also of value in a lathe in which the work spindle is angularly or vertically disposed.

Having thus described our invention and the advantages thereof, we do not wish to be limited to the details herein disclosed otherwise than as set forth in the claims, but what we claim is:—

1. In a lathe, in combination, a frame, a tool carriage slidable on said frame and supported thereby, a two-part pull rod for said carriage, means to adjust one part of said pull rod with respect to the other part, means to adjust the entire pull rod with respect to said carriage, cam mechanism operatively connected to move said rod and carriage, a work spindle, automatic means to move said spindle and cam mechanism in predetermined speed relation, and automatic means to vary said speed relation.

2. In a lathe, in combination, a frame, a tool carriage slidable on said frame and supported thereby, a pull rod for said carriage, cams operatively connected to move said pull rod and carriage, a work spindle, means to move said spindle and cams in predetermined speed relation, and means synchronized with said cams for varying said speed relation.

3. In a lathe, in combination, a frame, a tool carriage slidable on said frame and supported thereby, a pull rod for said carriage, cam mechanism operatively connected to move said pull rod and carriage, a work spindle, a main drive shaft, change speed connections between said main drive shaft and said spindle, means to drive said cam mechanism in predetermined speed relation to said spindle, and means synchronized with said cam mechanism to vary said speed relation.

4. In a lathe, in combination, a frame, a tool carriage slidable on said frame and supported thereby, a pull rod for said carriage, cam mechanism comprising a driven shaft having a cam on one end thereof in operative engagement with said pull rod, change speed mechanism operatively connected to the other end of said shaft, a main shaft connected to said change speed connection, a work spindle, change speed connections between said main drive shaft and said spindle, means to drive said cam mechanism in predetermined speed relation to said spindle, and means synchronized with said cam mechanism to vary said speed relation.

5. In a lathe, in combination, a tool carriage, a pull rod for said carriage, cam mech-

anism operatively connected to move said pull rod and carriage, a work spindle, a main drive shaft, change speed connections between said main drive shaft and said spindle, normally operating means to drive said cam mechanism in predetermined speed relation to said spindle, and additional means actuated in synchronism with said cam mechanism to drive said cam mechanism at a higher speed independent of said spindle speed, said normally operating means including an over-running clutch for connecting said drive shaft to said cam mechanism, and said additional means including a clutch through which said cam mechanism is actuated at high speed.

6. In a lathe, in combination, a tool carriage, a pull rod for said carriage, cam mechanism operatively connected to move said pull rod and carriage, a work spindle, a main drive shaft, change speed connections between said main drive shaft and said spindle, means to drive said cam mechanism in predetermined speed relation to said spindle, and additional means actuated in synchronism with said cam mechanism to drive said cam mechanism at a higher speed independent of said spindle speed, said latter means including a clutch for connecting said additional driving means to said cam mechanism, and an automatic means controlling said clutch.

7. In a lathe, in combination, a work spindle, a tool carriage, a pull rod for said carriage, cam mechanism operatively connected to move said pull rod and carriage, said cam mechanism comprising a cam having a drum rotatable therewith with cam portions thereon, and devices movable by said cam portions to control the speed of said spindle and cam mechanism and also to increase the speed of said cam mechanism relative to said spindle speed.

8. In a lathe, in combination, a tool carriage, a pull rod for said carriage, cam mechanism operatively connected to move said pull rod and carriage, a work spindle, means to move said spindle and cam mechanism in predetermined speed relation, and a give-way device in the connections to said cam mechanism, said device being also manually operable to stop said cam mechanism while said work spindle continues to rotate.

9. In a lathe, in combination, a tool carriage, a pull rod for said carriage, cam mechanism operatively connected to move said pull rod and carriage, a work spindle, means to move said spindle and cam mechanism in predetermined speed relation, said means including a ratchet clutch, and additional means to drive said cam mechanism at a higher speed, with said clutch over-running at said higher speed.

10. In a lathe, in combination, a tool carriage, a pull rod for said carriage, cam mech-

anism operatively connected to move said pull rod and carriage, a work spindle, means to move said spindle and cam mechanism in predetermined speed relation, a main drive shaft, a gear drive from said main shaft to said cam mechanism including a positive ratchet clutch, and a high speed belt drive between said main shaft and said cam mechanism, actuation by said belt drive running said cam mechanism at higher speed and causing said clutch to over-run.

11. In a lathe, in combination, a tool carriage, a pull rod for said carriage, cam mechanism operatively connected to move said pull rod and carriage, a work spindle, a starting device for said lathe, a locking device for retaining said starting device in position, a rotatable cam in said cam mechanism, and a trip on said cam effective to release said locking device and to thereby stop the lathe.

12. In a lathe, a frame, a tool carriage slidable on said frame, a pull rod for said carriage, a cam mechanism effective through said pull rod, to move said tool carriage axially of the frame, a tool slide on said carriage, a second cam mechanism on said carriage effective to move said tool slide toward and from the work, and means to actuate said two cam mechanisms in definite speed relation and means to automatically vary said relation.

13. The combination in a lathe as set forth in claim 12, in which means is provided for permitting predetermined lost motion between the pull rod and the carriage.

14. In a lathe, a tool carriage, a pull rod secured thereto, a cam roll fixed on said pull rod, a pair of cams engaging said roll on opposite sides thereof, and means to simultaneously rotate said cams.

15. In a lathe, a tool carriage, a cam drum mounted therein, a tool slide movable toward and from the work by said cam drum, a bearing for said drum, and means to move said bearing to adjust said drum axially.

16. In a lathe, a tool carriage, a cam drum mounted therein, a tool slide movable toward and from the work by said cam drum, a bearing for said drum, and means to move said bearing to adjust said drum axially, said bearing having a portion threaded in a part of said carriage and adjustable axially by rotation in said threaded part.

17. In a lathe, in combination, a frame, a tool carriage slidable on said frame and supported thereby, a tool slide transversely movable on said carriage, direct acting cam mechanism connected to move said carriage axially of the lathe, additional direct acting cam mechanism synchronized with said first mentioned mechanism for moving said slide toward and from the work, a work spindle, a main drive shaft for said cam mechanisms and said spindle, means to drive said spindle in predetermined speed relation to said cam

mechanisms, automatic devices for changing the speed of said spindle at predetermined points in the cycle of operation of said cam mechanism.

18. In a lathe, in combination, a frame, a tool carriage slidable on said frame and supported thereby, a tool slide transversely movable on said carriage, direct acting cam mechanism connected to move said carriage axially of the lathe, additional direct acting cam mechanism synchronized with said first mentioned mechanism for moving said slide toward and from the work, a work spindle, a main drive shaft for said cam mechanisms and said spindle, means to drive said spindle in predetermined speed relation to said cam mechanisms, automatic devices for changing the speed of said spindle at predetermined points in the cycle of operation of said cam mechanisms, and automatic means for increasing the speed of the carriage actuating cams during movement of the tool carriage in one direction.

19. In a lathe, in combination, a frame, a tool carriage slidable on said frame and supported thereby, a tool slide transversely movable on said carriage, direct acting cam mechanism connected to move said carriage axially of the lathe, additional direct acting cam mechanism synchronized with said first mentioned mechanism for moving said slide toward and from the work, a work spindle, a main drive shaft for said cam mechanisms and said spindle, means to drive said spindle in predetermined speed relation to said cam mechanisms, automatic devices for changing the speed of said spindle at predetermined points in the cycle of operation of said cam mechanisms, and automatic means for increasing and decreasing the speed of the carriage actuating cams during a single cycle of operation of the mechanism.

20. In a lathe, in combination, a frame, a tool carriage slidable on said frame and supported thereby, a tool slide transversely movable on said carriage, direct acting cam mechanism connected to move said carriage axially of the lathe, additional direct acting cam mechanism synchronized with said first mentioned mechanism for moving said slide toward and from the work, a work spindle, a main drive shaft for said cam mechanisms for said spindle, means to drive said spindle in predetermined speed relation to said cam mechanisms, automatic devices for changing the speed of said spindle at predetermined points in the cycle of operation of said cam mechanisms, and means for automatically stopping the lathe at a given point in the operation thereof.

21. In a lathe, in combination, a frame, a tool carriage slidable on said frame and supported thereby, a tool slide transversely movable on said carriage, direct acting cam mechanism connected to move said carriage axially

of the lathe, additional direct acting cam mechanism synchronized with said first mentioned mechanism for moving said slide toward and from the work, a work spindle, a main drive shaft for said cam mechanisms and said spindle, means to drive said spindle in predetermined speed relation to said cam mechanisms, automatic devices for changing the speed of said spindle at predetermined points in the cycle of operation of said cam mechanisms, automatic means for increasing the speed of the carriage actuating cams during movement of the tool carriage in one direction, and means for automatically stopping the lathe at a given point in the operation thereof.

22. In a lathe, in combination, a frame, a tool carriage slidable on said frame and supported thereby, a tool slide transversely movable on said carriage, direct acting cam mechanism connected to move said carriage axially of the lathe, additional direct acting cam mechanism synchronized with said first mentioned mechanism for moving said slide toward and from the work, a work spindle, a main drive shaft for said cam mechanisms and for said spindle, means to drive said spindle in predetermined speed relation to said cam mechanisms, automatic devices for changing the speed of said spindle at predetermined points in the cycle of operation of said cam mechanisms, means for automatically stopping the lathe at a given point in the operation thereof, means to start the operation of said lathe, means to lock said starting means, and means to unlock said starting means upon accidental obstruction to the movement of the tool carriage.

23. In a lathe, in combination, a frame, a tool carriage slidable on said frame and supported thereby, a tool slide transversely movable on said carriage, direct acting cam mechanism connected to move said carriage axially of the lathe, additional direct acting cam mechanism synchronized with said first mentioned mechanism for moving said slide toward and from the work, a work spindle, a main drive shaft for said cam mechanisms and said spindle, means to drive said spindle in predetermined speed relation to said cam mechanisms, automatic devices for changing the speed of said spindle at predetermined points in the cycle of operation of said cam mechanisms, automatic means for increasing the speed of the carriage actuating cams during movement of the tool carriage in one direction, means for automatically stopping the lathe at a given point in the operation thereof, means to start the operation of said lathe, means to lock said starting means, and means to unlock said starting means upon accidental obstruction to the movement of the tool carriage.

24. In a lathe, in combination, a frame, a tool carriage slidable on said frame and sup-

ported thereby, a work spindle, a main drive shaft for said carriage and said spindle, a pull rod for said carriage, cam mechanism operatively connected to move said pull rod and carriage, change speed connections between said main shaft and cam mechanism and between said main shaft and spindle, means to move said cam mechanism and spindle in predetermined speed relation, and means associated with said cam mechanism for actuating said change speed connections thereby to vary said speed relation.

In testimony whereof we have hereunto affixed our signatures.

EDWIN R. SMITH.
RICHARD A. ASHTON.
